(57) **CLAIM**

The ornamental design for post pot holder, as shown and described.

DESCRIPTION

FIG. 1 is a front perspective view thereof;

FIG. 2 is a front elevational view thereof, the rear elevational view being identical to the front elevational view;

FIG. 3 is a top plan view thereof;

FIG. 4 is a bottom plan view thereof; and,

FIG. 5 is a left side elevational view thereof, the right side elevational view being identical.

The portions of the article shown in broken lines form no part of the design.
